UNITED STATES PATENT OFFICE.

SURRY L. GREEN, OF FORT WORTH, TEXAS, ASSIGNOR OF ONE-HALF TO
CHARLES T. BELL, OF SAME PLACE.

DESIGN FOR A HOSE-SUPPORTER.

SPECIFICATION forming part of Design No. 33,094, dated August 21, 1900.

Application filed April 16, 1900. Serial No. 13,150. Term of patent 7 years.

To all whom it may concern:

Be it known that I, SURRY L. GREEN, a citizen of the United States, residing at Fort Worth, in the county of Tarrant and State of Texas, have invented and produced a new and original Design for a Hose-Supporter, of which the following is a specification, reference being had to the accompanying drawings, forming part thereof.

Figure 1 is a full view of the whole design, and Fig. 2 represents a cross-section of the article.

In the drawings, *b* represents the body, and *a* represent slots in the body, the slots being wider at the open ends and converging almost to points near the ends of the body, thereby forming a similarity to a V shape.

The object of my design is to furnish a new

and useful and ornamental hose-supporter consisting of a scroll resembling somewhat the letter **S** and having **V**-shaped slots therein, the narrow ends of the slots terminating toward the ends of the scroll.

Having fully described my invention, what I claim as new, and desire to secure by Letters Patent, is—

The design for a hose-supporter, as herein shown and described.

In testimony whereof I have signed my name to this specification in the presence of two subscribing witnesses.

SURRY L. GREEN.
